HAIR CURLER

Jacob G. Isaacs, Wilkes-Barre, and Michael F. Bonomo, Mountaintop, Pa.

Application April 7, 1952, Serial No. 280,894

2 Claims. (Cl. 132—42)

1

This invention relates to a means for curling hair more particularly to a means capable of being employed by an individual without the services of an attendant.

In the art of curling hair as generally practiced it is customary to roll a lock of hair comprising a number of individual strands about a mandrel and then to clamp the lock in coiled condition to the mandrel. Such practice requires that the lock be held on the mandrel at a distance from the head and then that the mandrel be rolled about its own axis toward the head while the lock is being coiled thereabout. The holding of the lock on the mandrel particularly during the initial stages of forming the curl has presented difficulties, and more especially when the curling of the hair is attempted without the services of an attendant. Many and various attempts heretofore have been made to devise means that will satisfactorily hold the hair on the mandrel during the rolling of the mandrel about its own axis but so far as we are aware no prior hair holding means has been devised that is capable of initially clamping a lock of hair tightly against the mandrel, and then clamping the rolled lock in tightly coiled relation about the mandrel. Moreover none of the devices with which we are familiar provide for clamping on a mandrel a thin lock composed of but a relatively few strands of hair as well as a thick lock containing a relatively large number of strands of hair.

The primary object of this invention is to facilitate the rapid coiling of a group of strands of hair about a mandrel and to retain the coiled strands in a coiled condition for as long a time as may be required to set a curl in the hair.

Another object is to tightly clamp, during the initial stages of curling hair, a lock of hair to be curled and after the hair has been coiled about the mandrel to clamp the lock in its coiled condition to the mandrel.

A further object is to securely clamp to a mandrel a lock of hair irrespective of the bulk of the lock, i. e. whether the lock is composed of a large or small number of strands of hair.

Still another object is to confine to the mandrel the hair comprising the lock to be curled and to avoid the slipping off of the mandrel of individual hairs contained in the lock.

A still further object is to vary the diameter of the mandrel and thereby to select the diameter of the curl to be made and to control the pressure by which the hair is clamped to the mandrel.

2

The above and other objects may be attained by employing this invention which embodies among its features a mandrel comprising an elongated circular cylindrical shank, flanges carried by the shank adjacent opposite ends thereof, said flanges extending outwardly from the periphery of the shank and having their adjacent faces lying perpendicular to the axis of the shank, said flanges having radial slots opening through their respective peripheries and extending to the periphery of the shank and a clamp comprising a length of flexible elastic material which when stretched longitudinally is adapted to be entered into the slots in the flanges at opposite ends of the shank and lie adjacent the shank for holding strands of hair coiled about the shank between the flanges.

In the drawings,

Fig. 1 is a perspective view of a hair curler embodying the features of this invention,

Fig. 2 is a side view of the curler showing portions thereof in section,

Fig. 3 is a side view of the elastic hair clamping means,

Fig. 4 is a perspective view of the curler showing the clamping means assembled therewith and ready for the application of a lock of hair thereto,

Fig. 5 is a view similar to Fig. 4 showing a lock of hair clamped to the mandrel preparatory to rolling the hair about the mandrel, and

Fig. 6 is a view similar to Fig. 5 showing the lock of hair rolled on the mandrel and clamped thereabout.

Referring to the drawings in detail this improved hair curler designated generally 10 embodies a mandrel which comprises an elongated circular cylindrical shank 12 carrying at opposite ends outwardly extending concentric flanges 14. Each flange 14 is provided with radially extending peripherally spaced slots 16 which extend from the periphery of the shank 12 through the peripheries of the flanges. These slots 16 are adapted to receive a clamp member 18 which comprises a length of elastic material which in its contracted state is of a diameter greater than the width of the slots but which when stretched longitudinally becomes so attenuated as to readily enter a slot 16.

In the preferred form of the invention the clamp member 18 is provided at one end with a handle 20 and at its opposite end with an enlargement 22 forming a positive stop that will restrain the clamp member 18 from pulling out of a slot 16 when under tension. A similar enlargement 24 is formed on the clamp member 18

between the handle 20 and the enlargement. The flanges 14 may if so desired be provided in the sides thereof remote from the shank 12 with recesses 26 which open into the slots 16 and receive the enlargements 22 and 24 and it is preferred that the slots 16 of one flange do not align with the slots 16 of the opposite flange 14 so that when the clamp member 18 is stretched between the flanges 14, it will lie in a spiral path with relation to the shank 12 to thus increase the clamping effect on the lock of hair being curled.

In use the clamp member 18 is stretched so that it can be entered into a slot 16 in the flange 14 at one end of the shank 12. The lock of hair to be coiled is then placed on the shank 12 as suggested in Fig. 5, and the clamp is then stretched longitudinally and entered into a slot 16 in the flange 14 at the opposite end of the shank 12. Obviously the clamp 18 may be entered in slots 16 nearest in line, or in case a greater clamping effort is to be exerted on the lock the clamp may be entered in other slots 16 so as to lie in a definite helix about the shank 12. With the lock of hair thus clamped to the shank 12, said shank may be rotated about its own axis to coil the lock about the shank 12. Because of the perpendicular faces on the flanges 14 all of the hair in the lock will be confined to the shank and when the scalp is approached, the coiled lock may be clamped in coiled position simply by stretching the extending portion of the elastic clamp member and extending it longitudinally adjacent the shank 12 on the outer side of the coiled lock and entering it into a slot 16 adjacent its initially secured end. The lock may be held in such coiled condition until such time as its removal is desired. Obviously the clamp member 18 may be removed from the slots 16 simply by pulling it radially away from the shank 12.

When it is desired to increase the diameter of the curls to be produced, a clamp member 18 is stretched and entered into oppositely disposed slots 16 to lie against the shank 12 and increase the effective diameter thereof.

While in the foregoing there has been shown and described the preferred embodiment of this

invention it is to be understood that minor changes in the details of construction, combination and arrangement of parts may be resorted to without departing from the spirit and scope of the invention as claimed.

What is claimed is:

1. A hair curler comprising an elongated circular cylindrical shank, flanges carried by the shank adjacent opposite ends thereof, said flanges extending outwardly from the periphery of the shank and having slots opening through their respective peripheries and extending radially inwardly to the periphery of the shank, a clamp comprising a length of flexible elastic material having a diameter greater than the width of the slots and being adapted to be stretched and attenuated to a diameter less than the width of the slots for entrance into slots in the flanges at opposite sides of the shank and holding a lock of hair clamped to the shank, said clamp having a generally spherical enlargement at one end of a slightly greater diameter than the width of said slots and a handle at its opposite end for securing the opposite end of said clamp and a second generally spherical enlargement intermediate its ends, which second enlargement has substantially the same diameter as said first enlargement.

2. The structure defined in claim 1 in which the radial slots in each disk are peripherally spaced equidistant from one another and in which the peripherally spaced slots in one disk lie out of registry with the slots in the other disk to cause the clamp member to lie in a helical path about the shank.
